UNITED STATES PATENT OFFICE.

WILLIAM MORRISON, OF DES MOINES, IOWA.

DYNAMO-ELECTRIC CLUTCH.

1,260,010.

Specification of Letters Patent.

Patented Mar. 19, 1918.

Original application filed September 18, 1913, Serial No. 790,538. Divided and this application filed December 2, 1914. Serial No. 875,161.

To all whom it may concern:

Be it known that I, WILLIAM MORRISON, a citizen of the United States, residing at Des Moines, in the county of Polk and State 5 of Iowa, have invented certain new and useful Improvements in Dynamo - Electric Clutches, of which the following is a specification.

My invention relates to a combined electromagnetic and friction clutch for automobiles. The electromagnetic clutch is preferably of the current self-generating type, having one rotor connected to the engine shaft and the other to the power shaft, and 10 is fully described in my Patents No. 1,126,060, dated January 26, 1915, Reissue No. 14,270, and No. 1,126,061, dated January 26, 1915, Reissue No. 14,271, of which 15 patents this application is a division. The friction clutch portion of the invention is of the centrifugal type, the two forms of 20 clutches being so constructed and arranged that the engine power is transmitted from the engine shaft to the driven shaft through the electromagnetic clutch, and the centrifugal clutch assists in transmitting the power, or itself serves as a completely effective 25 clutch between the two rotatable members at or above a predetermined speed.

The invention will be fully understood from the accompanying drawings, in which—

Figure 1 is a schematic representation of my invention as applied to an automobile;

Fig. 2 is a vertical section through the clutching mechanism;

Fig. 3 is an elevation of Fig. 2.

Referring to Fig. 1, 200 is the gas engine for driving the automobile, the engine 40 shaft A having secured thereto the drum or casing C'. To this drum is secured one rotor member of the dynamo-electric clutch, either the field magnet D' (Fig. 2) or the armature. The driven or power shaft B carries the other rotor member of the 45 dynamo, either the armature F' (Fig. 2) or the field magnet. The armature in the form shown in Fig. 2 has a commutator ring L', to which the electrical connections 50 are made in the usual way. Bearing against this commutator ring are brushes R', against which press springs S'. The connections between the field coils and brushes are not illustrated, as they are fully shown in 55 my prior applications aforesaid. When an external circuit, such as a storage-battery is

used, the dynamo is, preferably, arranged as a shunt-wound machine.

The shaft B has secured thereto a ring 30, to which is pivoted a number of arms 31, carrying at their outer ends adjustable weights 32. Springs 33, which may be adjustable, between the heels of the arms 31 and the ring 30, may normally prevent engagement of the weights 32 with the casing, or the 60 arms may be of spring metal and arranged to normally hold the weights 32 away from the casing, while permitting them to engage upon the development of sufficient centrifugal force. My device is applied to an automobile equipped in the usual way, power 70 being delivered to the driving axle through a suitable transmission-gear 80, the gears being shifted by the lever 203. The speed of the engine is varied or controlled by the 75 throttle 201.

The operation of the apparatus is as follows:—

Assuming the engine to be in operation, the power of the engine will be transmitted 80 through the electromagnetic clutch to the power shaft B, and the latter will be rotated at a speed differing from that of the engine shaft by the amount of slip between the two rotors of this clutch. As soon as the power 85 shaft B attains a speed of rotation corresponding to any desired speed of the automobile, the centrifugal weights will be thrown outwardly and will bear against the inner surface of the casing, thereby providing 90 a sliding, frictional engagement or clutch between the engine-shaft and power shaft.

The adjustment of the clutching power is effected by proper proportioning of the 95 weights, by varying their positions on the arms, by varying the springs or their tension, or by varying all these factors.

In practice, I prefer to adjust the centrifugal clutch so that up to a given or predetermined speed of travel, the main clutching action shall be that due to the electromagnetic clutch. When the predetermined speed is reached, the centrifugal clutch comes into play and the additional clutching effect 100 serves to prevent the "slip" between the rotors (with consequent development of excess current) from increasing to an undesirable degree. As the speed of the automobile increases, the clutching effect of the 105 centrifugal clutch becomes greater and greater, and may, if desired, be made suffi-

cient to, in effect, frictionally clutch together the two rotors, so that there may be little if any slip. Thus, with increasing speed of the driven shaft as the mechanical 5 clutching effect becomes greater, the electromagnetic clutching effect tends to become less, because the less the slip, the less the generation of current in the dynamo electric clutch. When the mechanical clutching effect 10 becomes so great that there is no slip and the two shafts are driven at the same speed, the electromagnetic effect due to generation of current is entirely absent.

By my invention therefore there are provided 15 two mutually coöperative clutching actions, the electromagnetic clutch efficiently transmitting the power from engine-shaft to power shaft at all lower speeds, while at higher and increasing speeds, the centrifugal 20 clutching action gradually becomes more and more effective. At all speeds, therefore, there is provided, in contradistinction to the rigid engagement of mechanically interlocked clutching devices, a yielding clutching effect by means of which jarring strains 25 are avoided.

I claim:—

1. A dynamo-electric clutch having revoluble field and armature elements and current collecting devices, in combination with a centrifugal clutch consisting of a friction member and a second centrifugally actuated member arranged for engagement with the friction member, the friction member being 30 connected to rotate with one rotor of the dynamo-electric clutch and the centrifugally actuated member connected to rotate with the other rotor of the dynamo-electric clutch.

2. The combination with a variable speed 40 engine, a driving shaft connected thereto, a driven load-shaft, and a dynamo-electric clutch having revoluble field and armature elements and current collecting devices, one rotor being connected to the driving shaft 45 and one to the driven shaft,—of a centrifugal clutch consisting of a friction member and a second centrifugally actuated member arranged for engagement with the friction member, the friction member being connected to rotate with one of said shafts and the centrifugally actuated member connected to rotate with the other shaft.

3. The combination with a variable speed engine, a driving shaft connected thereto, a 50 driven load-shaft, and a dynamo-electric clutch having revoluble field and armature elements and current collecting devices, one rotor being connected to the driving shaft and one to the driven shaft,—of a centrifugal 55 clutch consisting of a friction member connected to rotate with the driving shaft and a second centrifugally actuated member connected to rotate with the driven load-

shaft and arranged for engagement with the friction member.

4. In combination, a variable speed prime mover, a driving shaft connected thereto, a driven shaft, an electromagnetic clutch having one element connected to said driving shaft and the other element to said driven shaft, and auxiliary centrifugally operated means for coupling said shafts.

5. In combination, a variable speed prime mover, a driving shaft connected thereto, a driven shaft, an electromagnetic clutch having one element connected to said driving shaft and the other element to said driven shaft, and auxiliary centrifugally operated frictionally engaging means for coupling said shafts.

6. In combination, a variable speed prime mover, a driving shaft, a driven shaft, an electromagnetic clutching means between said shafts having an automatically decreasing clutching effect as the relative speed of the shafts decreases, and auxiliary mechanical clutching means between said shafts having an automatically increasing clutching effect as the speed of the driven shaft increases.

7. In combination, a variable speed prime mover, a driving shaft connected thereto, a driven shaft, an electromagnetic clutch between said shafts, and an auxiliary mechanical clutch connecting said shafts, the clutching action of which is dependent upon the speed of the driven shaft.

8. In combination, a variable speed prime mover, a driving shaft connected thereto, a driven shaft, an electromagnetic clutch coupling said shafts, and an auxiliary mechanical clutch coupling said shafts, the clutching action of the auxiliary mechanical clutch automatically increasing with the speed of the driven shaft.

9. In combination, a driving shaft, a driven shaft, a dynamo electric clutch coupling said shafts, and an auxiliary mechanical clutch coupling said shafts, the clutching effect of which is dependent upon the speed of the driven shaft.

10. In combination, a driving shaft, a driven shaft, an electromagnetic clutch coupling said shafts and having an automatically decreasing clutching effect as the relative speed of the shaft decreases, and an auxiliary clutch coupling said shafts having an automatically increasing clutching effect as the speed of the driven shaft increases.

In testimony whereof I affix my signature in presence of two witnesses.

WILLIAM MORRISON.
